UNITED STATES PATENT OFFICE.

ANSLEM J. BRYANT, OF MADDOX, MISSISSIPPI.

CLOTHES-LINE.

No. 893,702.

Specification of Letters Patent.

Patented July 21, 1908.

Application filed June 6, 1907. Serial No. 377,617.

To all whom it may concern:

Be it known that I, ANSLEM J. BRYANT, a citizen of the United States, residing at Mad-
5 dox, in the county of Simpson and State of Mississippi, have invented a new and useful Clothes-Line, of which the following is a specification.

This invention relates to clothes lines and its object is to provide an endless clothes
10 line which is of simple and durable construc-
tion and which is so formed that the same
can be operated to carry articles suspended
therefrom to points removed from the operator.

15 Another object is to provide a clothes line which is so constructed that the same will be positively moved by its actuating means.

A still further object is to provide simple
20 and efficient means for fastening clothes to
the line.

With these and other objects in view the invention consists of certain novel features of construction and combinations of parts which will be hereinafter more fully described
25 and pointed out in the claims.

In the accompanying drawings is shown the preferred form of the invention.

In said drawings: Figure 1 is an elevation of the clothes line embodying the present im-
30 provements; Fig. 2 is a plan view of a portion thereof and of its actuating device; and Fig.
3 is a perspective view of a portion of the de-
vice and showing a fastener thereon said fas-
tener being inverted.

35 Referring to the figures by characters of reference, 1 designates a support of suitable form having a short shaft 2 journaled in the upper portion thereof to which is secured a sprocket wheel 3 preferably constructed of wood and having concavities formed in its periphery producing pointed teeth 5. Another suitable support 6 is also provided and has a grooved wheel 7 journaled therein. This wheel and the sprocket 3 are designed
40 to support the clothes line which, as shown in Fig. 1, consists of a rope or cable 8, the ends of which are fastened to the ends of a chain 9, said cable and chain being prac-
tically of about the same length. The chain
45 is made up preferably of links each of which is formed of a single piece of wire bent into U-shape as shown at 10 in Figs. 2 and 3 and having eyes 11 formed at its terminals and designed to loosely engage the intermediate

portion 12 of the adjoining link. Certain of 55 the links carry pins or fasteners one of which has been shown in detail in Fig. 3. Each of these fasteners is formed of spring wire and is provided with substantially parallel arms 13 having eyes 14 at their ends which loosely 60 engage the side portions of one of the links. Each of the arms 13 merges into a loop 15 ex-
tending at right angles therefrom and the two loops are oppositely disposed and are spaced apart by an integral intermediate por- 65 tion 16. The free ends of the loops are out-
turned as shown at 17 and said loops con-
stitute a clip designed to embrace and bear upon the sides of the adjoining link of the chain. A crank 18 is secured to one end of 70 the shaft 2 and constitutes means whereby the line can be conveniently actuated manu-
ally.

In using the device herein described the articles to be dried are attached to the chain 75 line by swinging the loops 15 away from the chain and then replacing them so as to clamp upon the clothing. As the articles are placed on the line the sprocket 3 is rotated so as to move the line in the direction of its 80 length. The articles will therefore be car-
ried away from the sprocket 3. In Fig. 1 the line is shown in its initial position it being understood that when the clothes are sus-
pended therefrom the chain assumes a posi- 85 tion above the rope or cable 8. The proper position of the chain and one of its fasteners is shown in Fig. 3. It is of course apparent that clothing can be connected to the rope or cable 8 and fastened thereon by ordinary 90 clothes pins should it be desired. By pro-
viding a sprocket such as shown in Fig. 1 the same will adapt itself to the large chain links which are employed and will absolutely pre- 95 vent the line from slipping thereby insuring its positive actuation when the crank is turned. It is designed to extend lines such as herein described from porches or from the windows of buildings, the same being par-
ticularly desirable for such use because of the 100 fact that the articles can be connected thereto and then moved away from the porch or window and suspended above the ground and out of reach.

It is apparent that as clothes can not be 105 carried with the line around the sprocket or the pulley it is unnecessary to provide a chain the length of which is greater than the

distance between the sprocket and pulley and instead of making the entire line of a chain the cost of the device can be greatly reduced by providing a cable or rope connection 8 between the ends of the chain to complete the line. The rope is obviously much less expensive than the chain. Moreover, the rope can be more readily grasped than the chain for the purpose of drawing the line 10 without the aid of the crank 18. A still further object in providing a rope connection is the fact that the chain can be very readily adjusted to fit tightly upon the sprocket simply by shortening the rope, whereas 15 should the line be formed entirely of a chain the same could only be shortened or lengthened by the removal or the addition of a link. This would obviously require the use of some particular tools and could not be

done by a person inexperienced in handling 20 them.

What is claimed is:

The combination with supports and a chain carried thereby and shiftable longitudinally thereon; of a clothes fastener connected to 25 the chain and comprising spring arms loosely engaging one of the links of the chain, and oppositely disposed loops integral with the arms and constituting a clip disposed to extend across opposite sides of a link of the 30 chain.

In testimony that I claim the foregoing as my own, I have hereto affixed my signature in the presence of two witnesses.

ANSLEM J. BRYANT.
